[57] **CLAIM**

The ornamental design for a wheel, as shown and described.

DESCRIPTION

FIG. 1 is a front perspective view of a wheel showing my new design;

FIG. 2 is a front elevation view thereof;

FIG. 3 is a right side elevation view thereof;

FIG. 4 is a greatly enlarged fragmentary plan view thereof taken along line 4—4 in FIG. 3;

FIG. 5 is a greatly enlarged fragmentary sectional view thereof taken along line 5—5 in FIG. 4;

FIG. 6 is a greatly enlarged sectional view thereof taken along line 6—6 in FIG. 5; and

FIG. 7 is a greatly enlarged sectional view thereof taken along line 7—7 in FIG. 5.

The characteristic feature of the design resides in the provision of radially-disposed, axially-oriented circular openings, interspersed with alternating axially-offset spoke ends.
